UNITED STATES PATENT OFFICE

166,513

MARINE VESSEL

Walter Wiggins, Jr., Beaver Heights, Md.

Application September 27, 1951, Serial No. 16,760

Term of patent 14 years

(Cl. D71—1)

To all whom it may concern:

Be it known that I, Walter Wiggins, Jr., a citizen of the United States, residing at Beaver Heights, in the county of Prince Georges and State of Maryland, have invented a new, original, and ornamental Design for a Marine Vessel, of which the following is a specification, reference being had to the accompanying drawing, forming part thereof.

Figure 1 is a side elevation of a marine vessel, showing my new design;

Figure 2 is a top plan view thereof;

Figure 3 is a bottom plan view;

Figure 4 is a front end view;

Figure 5 is a rear end view, and

Figure 6 is a sectional detail, taken substan-

tially in the plane of the line 6—6 in Figure 1.

I claim:

The ornamental design for a marine vessel, as shown.

WALTER WIGGINS, JR.
